No. 619,303.

Patented Feb. 14, 1899.

N. L. HAYDEN & A. WILDMAN.

LOCOMOTIVE WATER PURIFIER.

(Application filed Mar. 22, 1897. Renewed Sept. 22, 1898.)

(No Model.)

UNITED STATES PATENT OFFICE.

NORMAN L. HAYDEN AND ANDREW WILDMAN, OF CHICAGO, ILLINOIS.

LOCOMOTIVE WATER-PURIFIER.

SPECIFICATION forming part of Letters Patent No. 619,303, dated February 14, 1899.

Application filed March 22, 1897. Renewed September 22, 1898. Serial No. 691,618. (No model.)

To all whom it may concern:

Be it known that we, NORMAN L. HAYDEN and ANDREW WILDMAN, citizens of the United States of America, residing at Chicago, in the county of Cook and State of Illinois, have invented certain new and useful Improvements in Locomotive Water-Purifiers, of which the following is a specification.

Our invention relates to certain improvements in a device for purifying water for use in steam-boilers, said improvements being designed especially for use upon locomotive-boilers.

The object of the invention is to devise an apparatus which shall effectually cleanse the water of all injurious ingredients, as well as of all dirt and sediment before it reaches the boiler, and to do this in a vessel of such a nature as to be easily accessible and readily cleaned.

To such end the invention consists in certain novel features embodied in the apparatus described in detail below, the essential portions of which will be definitely pointed out in the appended claim.

The preferred form of our invention is illustrated in the drawings presented herewith, in which—

Figure 1 is a side elevation of the entire apparatus, showing in vertical diametrical section the vessel which is intended to receive and collect the dirt and impurities; and Fig. 2 is a horizontal section in line 2 2 of Fig. 1.

Referring to the drawings, A is a steam-pipe leading from the boiler. B is a suction-pipe leading from the water-supply. C is an injector connected to both of said pipes.

D is the discharge-pipe of the injector, which leads therefrom to a vessel E, in which the impurities are to be collected. F is a pipe leading from said vessel E to the boiler.

G is a pipe connecting the pipe D with the pipe F and designed to cut out the vessel E when necessary.

H is a blow-off pipe intended for use in cleaning out the vessel E.

The steam-pipe and the suction-pipe are provided, respectively, with valves a b. The pipe D is provided with a check-valve d and a gate-valve d'. The pipe G is provided with a gate-valve g. The pipe F is provided with

a check-valve f, and the pipe H is provided with a valve h, adapted to close the same.

The vessel E is divided into an upper and a lower chamber by a partition e, made up of 55 perforated disks e' e'', between which is a loose filtering substance e''. The top of the vessel is covered by a cap e⁴, which may be removed, and the disks e' e'' are held between brackets e⁵ e⁶ e⁷ e⁸. Each of the disks is provided with notches e⁹ to enable them to pass by the brackets and with pivoted buttons e¹¹ to slip beneath the brackets and secure the disk in place. Beneath each of the disks is a reticulated fabric, preferably cloth, e¹². The 60 pipe D at the point where it enters the vessel E has a slight bend d², which is turned laterally and upwardly to direct the water against the cloth and in a direction substantially tangential with the wall of the vessel, 70 so as to cause a sort of whirlpool and assist in keeping the cloth free from sediment that might clog it up.

The operation of the device is as follows: The steam is turned on with the valves b d' 75 open. As the steam enters the injector it draws the water from the pipe B and delivers the same at a boiling temperature through the pipe D, past the check-valve d, and into the vessel E. The boiling of the water prepares 80 it to deposit the greater portion of its impurities which collect in the bottom of the vessel E. As the lower portion of this vessel fills the purer water at the top is forced upward through the cloth e¹², the filtering substance e'', the second cloth, and into the top of the vessel, from whence it passes on through the check-valve f to the boiler. The two thicknesses of cloth e¹² and the interposed filtering material thoroughly remove what- 85 ever sediment might otherwise fail to settle in the bottom of the vessel E. As the bottom of the latter fills up the valve h in the blow-off pipe is opened from time to time, discharging the sediment and impurities col- 90 lected. At much greater intervals the top e⁴ of the vessel is removed, the disks taken out, and the cloth or other reticulated fabric and interposed filtering material removed and renewed. This may all be done without in- 95 terfering with the feeding of the boiler, be- cause of the auxiliary pipe G, which furnishes 100

an independent connection between the injector and the boiler and enables the purifying vessel to be cut out entirely for cleaning.

We claim as new and desire to secure by

5 Letters Patent—

In a device for purifying water for boilers, the combination with a cylindrical vessel having a filtering partition perpendicular to the axis of the vessel, of a boiler - feeder

10 adapted to deliver water to said vessel at a boiling temperature, a pipe leading from said feeder into said vessel on one side of said partition and discharging the water into said vessel in a substantially tangential direction

and toward said partition, and a pipe leading 15 from said vessel upon the opposite side of said partition to the boiler; substantially as described.

In witness whereof we have hereunto set our hands, at Chicago, in the county of Cook 20 and State of Illinois, this 19th day of March, 1897.

NORMAN L. HAYDEN.
ANDREW WILDMAN.
